CLAIM

The ornamental design for an eyeglass frame display case,
as shown and described.

DESCRIPTION

FIG. 1 is a perspective view of the eyeglass frame display case according to our design, with two display cases shown in broken lines to illustrate a possible vertical arrangement.

FIG. 2 is a front view of an eyeglass frame display case as shown in FIG. 1.

FIG. 3 is a side view of one side of an eyeglass frame display case as shown in FIG. 1.

FIG. 4 is a top view of an eyeglass frame display case as shown in FIG. 1.

FIG. 5 is a rear view of an eyeglass frame display case as shown in FIG. 1.

FIG. 6 is a side view of the opposite side of an eyeglass frame display case as shown in FIG. 1; and,

FIG. 7 is a bottom view of an eyeglass frame display case as shown in FIG. 1.

The broken lines shown are for illustrative purposes only
and form no part of the claimed design.
